CHAIN DRILL

Dewey H. Goodman, Iowa Park, Tex.

Application March 2, 1936, Serial No. 66,746

4 Claims.

(Cl. 77—7)

The invention relates to boring tools and aims to provide a drill adapted to be power driven and portable and of a type to be held to the work by a chain or equivalent means.

- 5 The invention provides a tool that may be driven from a distant point by an automobile or other suitable and convenient source of power, and which may be thrown into and out of action at will, without stopping the motive power.
- 10 The invention furthermore provides a drill which admits of the bit being automatically thrown into and out of action by the pressure exerting means which, when applied, throws the bit into action and which, when released, throws the bit out of action.
- 15 A further purpose is the provision of a tool of the character aforesaid which allows changing of the bit at any time, when the tool is at rest or running, means being provided to release the bit by tapping a drift or rod.

20 While the drawings illustrate a preferred embodiment of the invention, it is to be understood that in adapting the same to meet specific needs and requirements, the design may be varied and changes in the minor details of construction may be resorted to within the scope of the invention as claimed, without departing from the spirit thereof.

25 For a full understanding of the invention and the merits thereof, reference is to be had to the following description and the drawings hereto attached, in which:

Figure 1 is a view illustrative of an embodiment of the invention driven by a motor vehicle.

30 Figure 2 is an enlarged detail sectional view of the tool.

Figure 3 is a sectional detail on the line 3—3 of Figure 2.

Figure 4 is a detail section on the line 4—4 of Figure 2.

Figure 5 is a view similar to Figure 4, on the line 5—5 of Figure 2.

Corresponding and like parts are referred to in the following description and designated in 45 the several views of the drawings by like reference characters.

The tool embodies a frame consisting of a hollow body 6 closed at its top by a bonnet 6a and at one side by a plate 6b. A drive shaft 7 is mounted in the frame and is formed with an axial opening to receive a bit stock 7b, drift rod 20 and expansible spring 18. The upper portion of the shaft 7 is reduced to provide a shoulder 7r and receive a feed tube 7u, anti-friction bearings 55 7e being interposed between the shoulder 7r and

the lower end of the tube 7u. A bit chuck is provided at the lower end of the bit stock and consists of the usual tapered opening 7m to receive the tapered shank of a bit 15. The drift rod 20 has a limited play in the drive shaft 7 and bit stock and engages the shank of the bit 15 to admit of releasing the bit by tapping upon the upper projecting end of the drift. The lower portion of the bit stock 7b has a loose fit in the axial opening 7o of the drive shaft and its upper portion 7k is reduced and has a close fit in a portion of the axial opening. The expansible spring 18 engages the bit stock and normally urges it downwardly and disengaged from the drive shaft. A square or non-circular portion 7f, of the opening 7o is adapted to receive a correspondingly shaped portion 7g of the bit stock when the latter is in clutched engagement with the drive shaft. These elements 7f and 7g constitute parts of a clutch which are normally held out of engagement by the spring 18 but which are in engagement when pressure is exerted through the feed member 7u to throw the bit into action. The bit stock has a limited play determined by a stop 21 and an annular recess 7i, the part 21 being threaded into 20 the drive shaft 7 and the recess 7i being formed in the bit stock.

A nut 7a retains the feed member 7u on the drive shaft 7, a thrust bearing 7s being interposed between the nut and the drive shaft. A longitudinal groove 7d formed in a side of the part 7u receives the inner end of a screw 19 applied to the bonnet 6a and prevents turning of the feeder. Cog teeth 7c formed in a side of the part 7u provide a rack which coacts with a pinion 16 fast to a shaft 16a mounted in the bonnet 6a. A bar 17 adjustable in a projecting end of the shaft 16a provides a handle for exerting a variable pressure to apply the bit.

Gearing 8 and 9 is mounted in the frame 6 and imparts motion to the drive shaft 7 from a suitable source of power, as a motor vehicle 22. The bevel gear 8 is splined to the drive shaft 7 to admit of the latter moving longitudinally. The bevel gear 9 is keyed to a socket 10 mounted in a tubular extension of the plate 6b and retained in place by a nut 11. A flexible shaft 12 transmits power from a suitable source and is protected by a covering 13. The shaft 12 is secured in any determinate way to the socket 10 and clamped to the axle of a motor vehicle 22 by fastening means 24, the drive wheel being jacked up, as indicated at 23.

Hooks 14 are applied to the frame 6 and engage links of a chain 25 to hold the drill to the work 55

26 when the tool is in operation. A groove 8b formed in a side of the shaft 7 receives a spline 8a which connects the shaft and bevel gear 8. When the tool is adjusted for action, power is 5 transmitted thereto from a suitable source by the shaft 12 or other preferred and convenient means. Upon rotating shaft 16a by means of the handle 17, the bit 15 is advanced and, at the same time, the clutch 7f-7g is engaged and rotation of the bit effected. A counter-rotation of the shaft 16a relieves the feed pressure exerted on the bit 15 and permits disengagement of the clutch and the idling of the drive shaft 7 without the necessity of stopping the motive power. At 10 this stage the bit 15 may be released, replaced, or adjusted. A tap on the drift rod 20 effects release of the bit as heretofore stated.

Having thus described the invention, what I claim is:

- 20 1. A boring tool comprising a frame, a drive shaft mounted therein for rotation and having a limited longitudinal movement therein, drive gearing splined to the drive shaft, a bit stock loosely mounted in the drive shaft and having an independent longitudinal movement therein, a clutch between the bit stock and drive shaft, a spring normally holding the clutch disengaged, a pressure member mounted on the drive shaft, and pressure exerting means for advancing the bit and throwing the clutch into engagement.
- 25 2. A boring tool comprising a frame, a drive shaft therein, a pressure member mounted on

the drive shaft, coating means between the frame and pressure member for advancing and retracting the latter, a bit stock slidably mounted within the drive shaft, a clutch disposed within the drive shaft and automatically operable by work resistance to the tool feed, and a spring located in the drive shaft and normally holding the clutch disengaged.

3. A boring tool comprising a frame, a drive shaft therein, a pressure member mounted on the drive shaft, coating means between the frame and pressure member for advancing and retracting the latter, means for preventing rotation of the pressure member relative to the frame, a bit stock slidable in the drive shaft, a clutch housed in the drive shaft and adapted to connect the bit stock thereto, and a spring disposed within the drive shaft and normally holding the bit stock disengaged from the drive shaft.

4. A boring tool comprising a frame, a drive shaft slidable in the frame, a pressure member carried by the drive shaft and held from rotation relative to the frame, means for moving the pressure member to control the feed, drive means mounted on the frame and splined to the drive shaft, a clutch and clutch disengaging spring within the drive shaft and housed thereby, and a drift rod passing through the drive shaft for detaching a bit therefrom and having the clutch disengaging spring mounted thereon.
